UNITED STATES PATENT OFFICE.

MEDERIC DROLET, OF KANKAKEE, ILLINOIS, ASSIGNOR TO IOWA WASHING MACHINE COMPANY, OF DES MOINES, IOWA, A CORPORATION.

GEARING.

1,129,280.

Specification of Letters Patent. Patented Feb. 23, 1915.

Application filed August 31, 1908. Serial No. 451,016.

To all whom it may concern:

Be it known that I, MEDERIC DROLET, a citizen of the United States, residing in the city of Kankakee, in the county of Kankakee and State of Illinois, have invented a new and useful Improvement in Gearing, of which the following is a specification.

My invention relates to certain improvements in gearing devices for washing machines of the class having an alternating rotary agitator and a balance wheel operatively connected therewith and having a speed increasing gearing applied to it.

My object is to provide a gearing device of this class of simple, durable and inexpensive construction in which the operating lever may be conveniently and easily moved by an operator who is either in a standing or sitting position and who may employ for actuating the lever either one or both hands and either or both feet or either one hand or one foot for operating the lever.

A further object is to provide a gearing of this class in which the rack bar is so connected to the operating lever and the pinion on the agitator shaft that the cover may be opened and closed without disconnecting these parts.

A further object is to provide a gearing device of this kind in which rapid or forceful movements applied to the operating lever will be centered as applied to the tub or support in such a manner as to avoid tilting the tub laterally.

My invention consists in certain details, in the construction, arrangement and combination of the various parts of the device, whereby the objects contemplated are attained, as hereinafter more fully set forth, pointed out in my claims and illustrated in the accompanying drawings, in which:

Figure 1 shows a vertical, sectional view of a gearing device for washing machines embodying my invention. Fig. 2 shows a sectional view thereof on the line 2-2 of Fig. 1. Fig. 3 shows a sectional view on the line 3-3 of Fig. 1, and Fig. 4 shows a view similar to the upper portion of Fig. 1 illustrating a modified construction.

Referring to the accompanying drawings, the reference numeral 6 is used to represent the tub referred to in the accompanying claims as the support. This tub is mounted upon legs 7 in the ordinary manner.

Within the tub is an agitator 8 mounted on

a vertical shaft 10 which passes through the cover 9, which cover is hinged at one side in the ordinary manner. On top of the agitator shaft 10 is a pinion 11. The upper end of said shaft is rotatably mounted in a bearing device 12 on top of the cover and it extends through a bearing 13 secured to the under surface of the cover.

For operating the agitator shaft I have provided a toothed rack 14 designed to mesh with the pinion 11 and being held in operative position relative to said pinion by means of the upright lug 17 formed on the bearing device 12, and arranged to permit an up and down movement of the rack bar 70 relative to the pinion. Mounted on one side of the tub is a bearing 18 in which is fulcrumed the upright lever 15. This lever is arranged to swing in a vertical plane toward and from a vertical line to the center of the 75 tub, and the lower end of the lever is inclined downwardly and outwardly away from the tub, so that the swing of the lever is not interfered with by the side of the tub. The rack 14 is necessarily offset from a vertical line through the center of the tub and in order to connect the lever with the rack, I provide a bracket 16 fixed to the lever 15 and offset laterally from the lever and having said rack 14 pivoted to it. The lever 15 80 is connected to the side of the tub adjacent to the hinged edge of the cover 9 so that said cover may swing to open position when the rack is in engagement with its pinion. On the lower end of the operating lever is a 90 stirrup device 20 extended laterally in both directions from the lever to thereby receive both or either one of the operator's feet, and fixed to the lever 15 above the bracket 16 is a double handle 85 extended laterally in both 95 directions and designed to receive both or either one of the operator's hands.

The advantages of having the operating lever constructed as shown and described are as follows: When the operator desires 100 to stand he may grasp the handle 15 at any point desired and suitable to his height and he may, if desired, place either one of his feet on the stirrup 20 to assist in operating the lever. Furthermore if the operator desires to be seated he may then very conveniently and easily grasp one of the handles, whichever is most convenient, and may also place one or both feet upon the stirrup. 105 110

2
In practice it has been found that if an operator will frequently change his manner of moving the operating lever as, for instance, first assuming a standing position 5 and grasping the upper end of the lever with one hand and then assuming a sitting position and using one hand and one foot, the machine can be run for a comparatively long time with little fatigue, whereas, in 10 machines of this class that can be operated only in one manner, the movement soon becomes tiresome to an operator.

In order to continue the motion applied by the lever for a period after the operator 15 ceases to move the lever, I have provided the following device: Arranged beneath the tub 6 are two crossed braces 28 fixed to the legs 7. Attached to these braces at a point spaced apart from the centers thereof is a 20 standard 27 having its lower end forked and secured to adjacent portions of the crossed braces as shown in Fig. 1 and also having its upper end forked and bolted to the bottom of the tub. Rotatably mounted on this standard 27 is a large cog wheel 24 and rotatably mounted in the standard 27 is a horizontally arranged balance wheel shaft 23 having a pinion 22 thereon in mesh with the cog wheel 24. The outer end of 30 the shaft 23 is supported in a bearing 26 on the bottom of the tub and a balance wheel 21 is fixed to said outer end to operate in a vertical plane and to overlap the side of the tub. I provide for connecting the lever 15 35 with the cog wheel 24 by means of a pitman 25 which pitman is connected to the lever 15 at a point spaced above the stirrup 20 so that it will not interfere with the operator's foot when on the stirrup and so that the 40 operator's foot may be as close to the floor as possible when operating the device.

In a machine of this kind it is very desirable that when rapid or forceful power is applied to the lever, it be applied in such 45 a manner that it will not tend to tilt the tub laterally. For this reason I have arranged the operating lever in position so that it can swing in a plane toward and from a line through the vertical center of the tub and 50 in order that this may be done, I have offset the bracket 16 from the side of the lever 15 to receive the straight rack 14 which of necessity must be at one side of the center of the tub. I have also set the standard 27 to 55 one side of the center of the tub so that the gear wheels 24 and 22 may be as close as practicable to the center of the tub in so far as this can be done when a pitman 60 25 is employed.

60 In the modified construction shown in Fig. 4, I show the operating lever as operating

the agitator by means of a swinging toothed segment 30 supported by a pivoted arm 31 and from a standard 32 on top of the cover. This segment meshes with the pinion 11 and 65 is connected to the lever 15 by the pitman 33. If preferred, this swinging segment may be substituted for the straight rack of the main figures. My invention also provides for swinging the cover from a closed to an upright open position, without the necessity as heretofore, of disconnecting any of the parts of the mechanism of the machine connected with the cover in any way.

I claim as my invention:

75 1. A gearing device for washing machines, comprising a support, a vertically arranged shaft mounted in the center of the support, a pinion thereon, a rack in mesh with said pinion, a horizontally arranged balance wheel shaft below the support, a balance wheel and a small pinion thereon, said pinion being arranged on one side of a vertical line through the center of the support, a gear wheel in mesh with said pinion 80 and also arranged on one side of a vertical central line through the support, a pitman connected with the gear wheel, a single operating lever fulcrumed to the side of the support and arranged to swing in a vertical plane toward and from a line through the center of the support, a bracket on the upper end of the operating lever offset laterally from the lever and connected to said rack, the lower end of the lever being connected 85 to said pitman, a handle at the upper end of the lever and a stirrup at the lower end, said stirrup being below said pitman.

2. A gearing device for washing machines, comprising a support, a vertical shaft mounted centrally in the top of the support, a pinion thereon, a lever fulcrumed to one side of the support and arranged in vertical position to swing in a plane toward and from a central vertical line through the support, 100 a bracket fixed to the lever and offset from one side thereof, a rack pivoted to said bracket and in mesh with the pinion on the upright shaft, a pitman fulcrumed to the lower end portion of the lever, a vertically arranged gear wheel offset from a central line through the support on the same side as the said rack bar is offset and having said pitman connected to it, a pinion in mesh 105 with said gear wheel, and a vertically arranged balance wheel connected to said pinion.

110 MEDERIC DROLET.
